ALFRED B. HEYES, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

HIGHWAY CROSSING PROTECTION

Application filed November 26, 1930. Serial No. 498,366.

My invention relates to highway crossing protection, that is, to apparatus for protecting the intersections of railways and highways.

5 I will describe one form of apparatus embodying my invention, and will then point out the novel features thereof in claims.

The accompanying drawing is a diagrammatic view illustrating one form of apparatus embodying my invention.

Referring to the drawing, the reference characters 1 and 1^a designate the track rails of a stretch of railway track over which traffic normally moves in the direction indicated by the arrow. These track rails are divided by means of insulated joints 2, to form a plurality of track sections, of which only one complete section D—E is shown in the drawing. A highway M intersects this section at 10 a point some distance in advance of the point D.

Section D—E is provided with the usual track circuit comprising a transformer T, the secondary 3 of which is connected across the rails at the exit end of the section, and a track relay L connected across the rails at the entrance end of the section. The primary 4 of transformer T is constantly connected with the terminals B and C of a suitable 15 source of alternating current not shown in the drawing.

Section D—E is also provided with a time element relay A, and with a checking relay F. The time element relay A may be of any suitable type, and as here shown, is provided with the usual time element contact 6 which becomes opened at the expiration of a comparatively long adjustable time interval after the relay becomes energized. Relay A is also provided with a checking contact 7 which becomes closed, upon deenergization of the relay, as soon as the operating mechanism of the relay has restored it 20 to its normal deenergized condition, and which opens, upon energization of the relay, as soon as the operating mechanism has started to function. Relay A is controlled by a back contact 5 of track relay L, so that relay A will become energized whenever track relay L becomes deenergized. Checking relay

F is controlled by checking contact 7 of relay A, and will therefore be energized whenever relay A is deenergized, provided relay A is operating in its normal manner.

The relays L, A and F control a slow-releasing signal relay K which, in turn, controls a highway crossing protective device of any suitable type. As here shown, the highway crossing protective device is an electric bell S, which is connected with the terminals B 55 and C of the source over a back contact 8 of relay K, so that this bell will ring whenever relay K is deenergized.

Relay K is provided with a circuit which passes from terminal B through time element contact 6 of relay A, front contact 9 of relay L, and the winding of relay K to terminal C. This circuit is provided with a branch around front contact 9 of relay L including back contact 10 of relay F. 60

Traffic over section D—E is controlled by a wayside signal J which, in the form here shown, is a light signal comprising three electric lamps G, Y and R arranged when energized to indicate "proceed", "caution" and "stop", respectively. As here shown, signal J is controlled by relays L and F, and by a distant relay H. The distant relay H, in turn, is controlled by a front contact 11 of the track relay L¹ for the section to the right 65 of point E in such manner that this relay will be energized or deenergized according as the section to the right of point E is unoccupied or occupied.

Lamp G of signal J is provided with a circuit which passes from terminal B through front contact 12—12^a of track relay L, front contact 13—13^a of checking relay F, front contact 14—14^a of distant relay H, and the filament of lamp G to terminal C. When 70 this circuit is closed, lamp G is lighted and signal J indicates proceed. Lamp Y of signal J is provided with a circuit which passes from terminal B through front contact 12—12^a of track relay L, front contact 13—13^a of checking relay F, back contact 14—14^b of distant relay H, and the filament of lamp Y to terminal C. When this circuit is closed, lamp Y is lighted, and signal J indicates 75 caution. Lamp R of signal J is provided 80

with a circuit which passes from terminal B, through back contact 12-12^b of relay L and the filament of lamp R to terminal C. Lamp R is also provided with another circuit which

5 passes from terminal B, through front contact 12-12^a of relay L, back contact 13-13^a of checking relay F, and the filament of lamp R to terminal C. When either of these circuits for lamp R is closed, lamp R is lighted, 10 and signal J indicates stop.

As shown in the drawing, section D-E and the section to the right of point E are both unoccupied. Track relays L and L¹ are therefore both energized. Since track relay 15 L is energized, time element relay A is de-energized. The circuit for relay F is therefore closed at checking contact 7 of relay A, and the circuit for signal relay K is closed at time element contact 6 of relay A and at 20 front contact 9 of relay L. Relays F and K are therefore both energized. Since relay K is energized, the circuit for bell S is open at back contact 8 of this relay, and bell S is therefore deenergized. Distant relay H is 25 energized, and the circuit for lamp G of signal J is therefore closed, so that signal J displays a proceed indication.

In explaining the operation of the apparatus, I will first assume that with the parts 30 in the conditions just described, a train moving in the direction of the arrow enters section D-E. This deenergizes track relay L, so that relay L opens its front contacts 9 and 12-12^a, and closes its back contacts 5 and 12-12^b. The opening of front contact 12-12^a of relay L interrupts the circuit for lamp G of signal J, and the closing of back contact 12-12^b completes the circuit for lamp R. Lamp G therefore becomes extinguished, and lamp R becomes lighted to indicate to any following train that section D-E is occupied. The opening of front contact 9 of relay L interrupts the circuit for relay K, but this circuit only remains open for a short 40 interval of time, because the closing of back contact 5 of relay L causes time element relay A to become energized, and if relay A is operating in the normal manner, contact 7 of this relay opens and relay F immediately becomes deenergized, to complete the branch around contact 9 at its back contact 10. Relay K is made sufficiently slow-releasing, so that it holds its front contact 8 open during the interval of time which elapses between 45 the opening of contact 9 and the closing of contact 10, and it will be apparent, therefore, that bell S does not become energized under these conditions. When the time interval for which the time element contact 6 of relay A is set, has expired, however, time element contact 6 opens, and the circuit for relay K is then interrupted at this contact. Relay K therefore now becomes deenergized and closes its back contact 8 so that bell S starts 50 to ring, thereby warning users of the highway

that a train is approaching on the railway. In actual practice, contact 6 will usually be so adjusted, and the parts will be so proportioned, that bell S will not start to ring after a train has entered section D-E until the 70 train, when traveling at the fastest speed at which it is permitted to approach the highway, is at the minimum distance away from the highway which will permit users of the highway to safely clear the railway. 75

When the train enters the section to the right of point E, track relay L¹ becomes de-energized and deenergizes distant relay H. This has no effect on the remainder of the apparatus under these conditions, however, because both circuits controlled by this relay are then open at front contact 12-12^a of relay L. When the train has passed completely out of section D-E, track relay L again picks up, thereby closing its front contacts 9 and 12-12^a and opening its back contacts 5 and 12-12^b. The opening of front contact 5 of relay L deenergizes relay A which immediately closes its checking contact 7 and its time element contact 6. The closing of time element contact 6 completes the circuit for relay K, and the closing of checking contact 7 completes the circuit for relay F. Relays K and F therefore both become energized. When relay K becomes energized, the circuit for bell S is interrupted, and bell S therefore stops ringing. When front contact 13-13^a of relay F becomes closed, the circuit for lamp Y of signal J is completed, the circuit for lamp R having previously been interrupted at contact 12-12^b when relay L became energized. Lamp Y therefore becomes lighted to indicate that section D-E is unoccupied, but that the section to the right of point E is occupied. 100 When the train passes out of this latter section, track relay L¹ becomes energized which, in turn, energizes distant relay H. When back contact 14-14^b of relay H opens, it interrupts the circuit for lamp Y of signal J, and when front contact 14-14^a becomes closed, it completes the circuit for lamp G. Lamp Y therefore becomes extinguished, and lamp G becomes lighted, so that the parts are then restored to the conditions in which they 110 are illustrated in the drawing. 115

I will now assume that with the parts in their normal condition, a train enters section D-E, and deenergizes track relay L, but that time element relay A fails to operate, due for example, to a broken wire, or to a short-circuited winding. Under these conditions, checking contact 7 of time element relay A remains closed, and checking relay F therefore remains energized, so that its back contact 10 remains open. As a result, the branch for the circuit for relay K around front contact 9 of relay L which normally becomes closed at contact 10 of relay F shortly after relay L becomes deenergized, now remains 120 125 130

open, and relay K therefore closes its back contact 8 under these conditions as soon after relay L has become deenergized as the time interval required for this relay to release has expired. When contact 8 of relay K is closed, bell S starts to ring, and it will be apparent, therefore, that if relay A fails to operate in the normal manner when a train enters section D—E, bell S instead of remaining deenergized for the comparatively long interval of time normally required for relay A to open its time element contact, will become energized at the expiration of the comparatively short interval of time necessary for relay K to release after relay L has become deenergized.

I will now assume that when a train enters section D—E and deenergizes relay L, time element relay A picks up in the normal manner, and causes bell S to ring, but that, when the train has passed out of this section, the relay fails to restore itself to its normally deenergized condition after track relay L picks up. Under these conditions, checking contact 7 of relay A remains open, so that relay F remains deenergized. The circuit for lamp R of signal J including front contact 12—12^a of track relay L and back contact 13—13^b of relay F is then closed, and lamp R therefore remains lighted even though distant relay H now becomes energized due to the train having passed completely out of the section to the right of point E. As a result, when a following train approaches signal J, it receives a stop indication, and when this signal fails to clear after a reasonable length of time, the improper operation of the time element relay will be detected. Furthermore, relay K now remains deenergized, and bell S will therefore continue to ring until the time element relay is repaired.

It will be apparent, therefore, that with apparatus embodying my invention, failure of the time element relay to function in its normal manner will not cause a dangerous condition to exist at the highway.

It should be pointed out that since the time interval which elapses between the deenergization of relay L and the opening of time element contact 6 is adjustable, the crossing signal may be made to operate at the expiration of any desired time interval after the train enters section D—E. This permits the apparatus to be readily adapted to sections having different distances between the entrance end of the section and the highway, and over which trains travel at different rates of speed, and makes it possible to control the highway crossing protective device by the usual track circuit which is employed to control the railway signals without the use of cut sections or other similar auxiliary control means.

It should also be pointed out that, for the purpose of describing my invention, I have

illustrated signal J as controlled by traffic conditions only in section D—E, and the section to the right of point E. This arrangement is not essential, however, and the signal may in actual practice be controlled also by means responsive to traffic conditions in advance in accordance with any well-known system of railway signaling.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track intersected by a highway, a track circuit for said section including a track relay, a time element relay controlled by said track relay, said time element relay being provided with a checking contact which becomes operated immediately upon energization of the relay and a time element contact which becomes operated at the expiration of a comparatively long time interval after the relay becomes energized, a checking relay controlled by said checking contact, a signal relay, means for controlling said signal relay controlled by said track relay and said checking relay and including said time element contact, and a crossing protective device located at the intersection of said highway and said section and controlled by said signal relay.

2. In combination, a section of railway track intersected by a highway, a track circuit for said section including a track relay, a time element relay controlled by said track relay, said time element relay being provided with a checking contact which becomes operated immediately upon energization of the relay and a time element contact which becomes operated at the expiration of a comparatively long time interval after the relay becomes energized, a checking relay controlled by said checking contact, a signal relay, a circuit for said signal relay including said time element contact and a front contact of said track relay, said circuit being provided with a branch around said front contact of said track relay including a back contact of said checking relay, and a highway crossing signal located at the intersection of said highway and said section and controlled by said signal relay.

3. In combination, a section of railway track intersected by a highway, a track circuit for said section including a track relay, a time element relay controlled by a back contact of said track relay, said time element relay being provided with a normally closed checking contact which becomes opened as soon as the relay becomes energized and with

a normally closed time element contact which remains closed after the relay becomes energized until the expiration of a time interval of comparatively long duration, a checking relay controlled by said checking contact, a slow releasing signal relay, a circuit for said signal relay including said time element contact and a front contact of said track relay, said circuit being provided with a branch around said front contact of said track relay including a back contact of said checking relay, and a highway crossing protective device located at the intersection of said highway and said section and controlled by a back contact of said signal relay.

4. In combination, a section of railway track intersected by a highway, a track circuit for said section including a track relay, a time element relay, means controlled by a back contact of said track relay for energizing said time element relay, said time element relay being provided with a normally closed checking contact which opens immediately upon energization of the relay and with a normally closed time element contact which becomes opened at the expiration of a comparatively long time interval after the relay becomes energized, a slow releasing signal relay, a circuit for said signal relay including said time element contact and a front contact of said track relay, means controlled by said checking contact for shunting said front contact of said track relay upon energization of said time element relay, said signal relay being sufficiently slow releasing to bridge the interval of time which normally elapses between the opening of said front contact and the operation of said shunting means, and a highway crossing signal located at the intersection of said highway and said crossing and controlled by a back contact of said signal relay.

5. In combination, a section of railway track intersected by a highway, a track circuit for said section including a track relay, a time element relay controlled by said track relay and arranged to become energized upon deenergization of said track relay, said time element relay being provided with a normally closed contact which becomes opened at the expiration of a predetermined time interval after the relay becomes energized, a slow releasing signal relay controlled by said time element contact and a front contact of said track relay, means controlled by said time element relay and effective when said time element relay becomes energized for normally bridging said front contact of said track relay before said slow releasing relay has become deenergized, and a crossing protective device located at the intersection of said highway and said section and controlled by said signal relay.

6. In combination, a section of railway track intersected by a highway, a track circuit

for said section including a track relay, a time element relay controlled by said track relay, a checking relay controlled by said time element relay, a signal relay controlled by said time element relay and said track relay as well as by said checking relay, a crossing protective device located at the intersection of said highway and said section and controlled by said signal relay, and a signal for said section controlled in part by said checking relay.

7. In combination, a section of railway track intersected by a highway, a track circuit for said section including a track relay, a time element relay controlled by a back contact of said track relay, said time element relay being provided with a normally closed checking contact which becomes opened as soon as the relay becomes energized and with a normally closed time element contact which remains closed after the relay becomes energized until the expiration of a time interval of comparatively long duration, a checking relay controlled by said checking contact, a slow releasing signal relay, a circuit for said signal relay including said time element contact and a front contact of said track relay, said circuit being provided with a branch around said front contact of said track relay including a back contact of said checking relay, a highway crossing protective device located at the intersection of said highway and said section and controlled by a back contact of said signal relay, and a signal for said section controlled in part by said checking relay in such manner that when said checking relay is deenergized said signal will indicate stop.

8. In combination, a section of railway track intersected by a highway, a track circuit for said section including a track relay, a time element relay controlled by a back contact of said track relay, said time element relay being provided with a normally closed checking contact which becomes opened as soon as the relay becomes energized and with a normally closed time element contact which remains closed after the relay becomes energized until the expiration of a time interval of comparatively long duration, a checking relay controlled by said checking contact, a slow releasing signal relay, a circuit for said signal relay including said time element contact and a front contact of said track relay, said circuit being provided with a branch around said front contact of said track relay including a back contact of said checking relay, a highway crossing protective device located at the intersection of said highway and said section and controlled by a back contact of said signal relay, a distance relay controlled by traffic conditions in advance of said section in such manner that said relay is energized or deenergized according as traffic conditions in advance are safe or unsafe, a signal for controlling traffic over said sec-

- tion comprising a proceed lamp, a caution lamp, and a stop lamp; a circuit for said proceed lamp including a front contact of said track relay, a front contact of said checking relay, and a front contact of said distant relay; a circuit for said caution lamp including a front contact of said track relay, a front contact of said checking relay, and a back contact of said distant relay; a first circuit for said stop lamp including a back contact of said track relay, and a second circuit for said stop lamp including a front contact of said track relay and a back contact of said checking relay.
9. In combination, a section of railway track intersected by a highway, a track circuit for said section including a track relay, a time element relay controlled by said track relay, a highway crossing signal located adjacent the intersection of said section and said highway, and means for controlling said signal controlled by said track relay and said time element relay in such manner that if said time element relay is operating in its normal manner said signal will become energized at the expiration of a predetermined time interval of comparatively long duration after a train enters said section but that if said time element relay fails to operate in its normal manner said signal will become energized at the expiration of a comparatively short time interval after a train enters said section.

In testimony whereof I affix my signature.
